UNITED STATES PATENT OFFICE

ROGER K. LEE, OF HIGHLAND PARK, MICHIGAN, ASSIGNOR TO CHRYSLER CORPORATION, OF DETROIT, MICHIGAN, A CORPORATION OF DELAWARE

DESIGN FOR A RUNNING-BOARD MAT

Application filed July 2, 1930. Serial No. 36,253. Term of patent 7 years.

To all whom it may concern:

Be it known that I, ROGER K. LEE, a citizen of the United States, residing in the city of Highland Park, county of Wayne, and State of Michigan, have invented a new, original, and ornamental Design for a Running-Board Mat, of which the following is a specification, reference being had to the accompanying drawings, forming a part thereof, in which:

Fig. 1 is a top plan view of a running board mat, showing my new design.

Fig. 2 is a side elevation of Fig. 1.

Fig. 3 is an enlarged sectional view taken on line 3—3 of Fig. 1 showing one end in perspective.

I claim:

The ornamental design for a running board mat substantially as shown.

ROGER K. LEE.
